UNITED STATES PATENT OFFICE.

JAMES A. McLAIN AND HARRY A. BROOKS, OF LOS ANGELES, CALIFORNIA; SAID BROOKS ASSIGNOR, BY MESNE ASSIGNMENTS, TO GEORGE M. HARKER, OF LOS ANGELES, CALIFORNIA.

DOOR-LOCK.

981,099.

Specification of Letters Patent. Patented Jan. 10, 1911.

Application filed October 21, 1909. Serial No. 523,912.

To all whom it may concern:

Be it known that we, JAMES A. McLAIN and HARRY A. BROOKS, both subjects of the King of Great Britain, residing at Los Angeles, in the county of Los Angeles, State of California, have invented a certain new and useful Door-Lock; and we do hereby declare the following to be a full, clear, and exact description of the invention, such as will enable others skilled in the art to which it appertains to make and use the same.

This invention relates to door locks, and has for one of its objects to provide a simple and compact construction therefor which shall embody novel advantageous features and be durable and effective in use.

Another object of the invention is to provide a lock which may be installed in a door with a minimum amount of labor by being fitted in openings easily made by an auger, and in which the key hole, by being placed in the knob on the outside, can be easily found for inserting a key.

Still another object is to provide a setting mechanism for the lock which can be readily operated to permit withdrawal of the bolt by the turning of either the inside knob or the outside knob, or to permit withdrawal of the bolt by turning the outside knob after a suitable key has been inserted in the lock, or to permit locking the bolt against withdrawal by manipulation of either the inside knob or the outside knob even when the proper key has been inserted in the lock.

Other objects and the advantages of the invention will be apparent to those skilled in the art, from a consideration of the following description of one form of construction which embodies it, taken in connection with the accompanying drawings, in which—

Figure 1 is a horizontal central section through the lock fitted in a door; Fig. 2 is a section on line 2—2 of Fig. 1; Fig. 3 is a perspective detail of a part of the dead-lock mechanism and bolt; Fig. 4 is an elevational fragmentary detail of the bolt-withdrawing mechanism; Fig. 5 is an elevation of a portion of the edge of the door showing end of bolt and guide-plate; Fig. 6 is a section through the inside knob with contained parts in elevation; and Fig. 7 is a detail of the dog.

As shown, the lock may be fitted in the

stile 2 of the door, having therein circular intersecting holes 3 and 4, which latter may be made with an ordinary auger of suitable diameter. Hole 3 may have a lining 5 and in the inner end thereof a spring 6 bearing 60 against the head 7 of bolt 8, which latter has its outer end disposed in guide-plate 9 and is provided with a slot 10 near its head 7. In hole 4 is disposed a tube 11 passing through slot 10 of bolt 8 and having arranged therein a rod 12. The hollow outside knob 13, preferably of chilled steel, has affixed thereto sleeve 14, which extends over tube 11 and near its inner end is secured by screw 15, which latter, when the parts of the 70 lock are assembled, is concealed and out of reach from the outside in consequence of the end of the sleeve being fitted in a bushing 16 disposed in the outside end of opening 4, as will readily appear from Fig. 1 of the 75 drawings.

In knob 13 is arranged any suitable mechanism 52, operable by a suitable key 53 to move rod 12 to the right, for a purpose hereinafter mentioned. As shown, the 80 mechanism 52 may consist of a part 54 integral with sleeve 14 and provided with a recess 55 in which, as in a common type of lock, is disposed a cylinder 56 which has therein openings (not shown, because common in a form of Yale lock), with pins therein which are adapted to move the plungers 57 out of the opening and flush with the surface of the cylinder, to permit movement of the cylinder when the key 53 85 is inserted therein. The tube 11 extends, on the inside of the door, through hollow inside knob 17; the latter being made up of half parts 18 and 19. The part 18 carries a sleeve 20 having its end disposed in bushing 95 21 fitted at the inside end of opening 4. On the interior of sleeve 20 is secured, preferably by screw 21, the sleeve 22, one end of which adjacent to the right side of bolt 8 is provided with a cam 23 adapted to engage lugs 100 23^a on bolt 8 when the inside knob is turned; its other end extending into part 18 of knob 17, as shown in Fig. 1. A dog 25, provided with an opening 26 to accommodate the tube 11, and provided with lugs 27, is carried by 105 rod 12 at its end in knob 17 by means of a pin 28 having its ends guided in slots 29 on each side of tube 11. The dog 25 is provided with one or more teeth 30 adapted to mesh with the teeth 31 of a circular rack 32 110

on the interior wall of part 18 of knob 17. Disposed between the dog 25 and a shoulder 33 on sleeve 20, is the setting mechanism 34, which may consist of a part 35, adjacent to shoulder 33, loosely mounted on sleeve 22 and provided with handle 36 passing through a slot 36^a in part 18 of knob 17, and a part 37, adjacent to dog 25, slidably mounted on the sleeve 22 and guided by pin 38 in slot 39 in the sleeve, the parts 35 and 37 having suitable cam surfaces in contact, as shown. A spring 40 is interposed between dog 25 and a washer 41 near the end of tube 11. The part 19 may be provided with projections 42, fitting indents 43 in part 18 to prevent rotation relatively thereto, and may be held in place by flange 44 on washer 41, by means of a screw 45 fitted in tube 11 and having its head 46 bearing against the flange. To the left of bolt 8 is the dead-lock mechanism, which may comprise an annular disk 47 movable on tube 11 to engage projections 48 on bolt 8, the disk being provided with a flange 49 whereby it is secured to rod 12 by means of a pin 50 guided in slots 51 in tube 11.

As will readily be understood, the lock may be installed in the door by first placing in the hole 3 the lining 5, spring 6, bolt 8 and guide-plate 9. Then by mounting on tube 11, with rod 12 therein, the outside knob and sleeve, the bushing 16 and disk 47, and passing the parts so mounted into the opening 4 from the outside of the door to have the tube 11 pass through the slot 10 of bolt 8, whereupon there may be mounted upon the tube 11 from the inside of the door, the sleeve 22, sleeve 20 secured thereto, the parts 35 and 37 on sleeve 22, dog 25 on rod 12, spring 40, part 19 of the inside knob, washer 41 loosely mounted between the tube and part 19, and finally screw 45 may be fitted in the tube.

The operation of the lock as above described may be as follows: The handle 36 of the setting mechanism may be moved to occupy a middle position in slot 36^a (Fig. 2), in which case the dog 25 engages the circular rack 32 in the inside knob 17 and the inside and outside knobs are mechanically interlocked so that by turning either knob the bolt 8 may be withdrawn. When the handle is moved to either the right or left of the middle position, the dog 25 is moved either to the rear or front of the circular rack 32 out of engagement therewith. In case the dog is moved to the rear of the circular rack 32, the rod 12 is moved to engage the head portion of cylinder 56, and though the bolt 8 may be withdrawn by turning the inside knob, the inside and outside knobs are not mechanically interlocked until the key is inserted in cylinder 56 to move it and thereby the rod 12, to bring the dog on the rod into engagement with the

circular rack. When the handle is moved to bring the dog to the front of the circular rack, the dead-lock mechanism is brought into play, so that neither the inside nor outside knobs can be turned to effect withdrawal of the bolt on account of the disk 47 being moved to a position to engage the projections 48 on the bolt, as will be understood.

While one form of apparatus in which the invention may be embodied has been illustrated and described, it is obvious that various modifications and changes may be made, and the right is reserved to all such modifications and changes as do not depart from the spirit and scope of the invention.

We claim:

1. In a door lock, in combination, a spring-pressed bolt, a sleeve passing through said bolt, a knob secured to said sleeve at one end thereof, a second knob loosely mounted on said sleeve at the other end thereof, means on the second knob to engage said bolt to withdraw it, means carried by said sleeve and in said second knob for mechanically interlocking said knobs, and key-controlled means in the first knob for actuating said last means.

2. In a door lock, in combination, a spring-pressed bolt, a sleeve, a knob secured to the sleeve at the outer side of the door, a knob loosely mounted on the sleeve at the inner side of the door, means on the last knob for effecting withdrawal of the bolt, means including a rod in said sleeve to mechanically interlock the knobs, means on the rod to engage the bolt to deadlock the bolt, and setting mechanism at the inner side of the door operable at will to actuate either the second mentioned means or the means to deadlock the bolt.

3. In a door lock, in combination, a spring-pressed bolt, a sleeve, a knob affixed to said sleeve at one end thereof, a second knob loosely mounted on said sleeve at the other end thereof, a rod extending between the knobs and arranged in said sleeve slidably and nonrotatively thereto, means carried by said second knob to engage said bolt to withdraw it, means on said rod and on said second knob adapted to interlock so that turning of the first knob will effect withdrawal of the bolt, setting mechanism in the second knob associated with said means, and key-controlled means in the first knob to render the interlocking means effective through the aid of the rod.

4. In a door lock, in combination, a spring-pressed bolt having lugs and projections thereon, a sleeve passing through said bolt, a knob affixed to said sleeve at one end thereof, a second knob mounted on said sleeve at the other end thereof, a rod extending between the knobs and passing through said sleeve, means carried by said second

- 5 knob adapted to coact with said lugs in effecting withdrawal of said bolt, means on said rod and in said second knob adapted to coact to mechanically interlock said knobs, and means on said rod to engage said projections to deadlock the bolt.
5. In a door lock, in combination, a spring-pressed bolt, a sleeve, a knob affixed to said sleeve at one end thereof, a second 10 knob loosely mounted on said sleeve at the other end thereof, a rod arranged in said sleeve slidably and nonrotatively thereto, means carried by the second knob to engage the bolt to withdraw it, means on said rod 15 and on said second knob adapted to interlock so that turning of the first knob will effect withdrawal of the bolt, and means in said first knob movable to engage said rod to render said interlocking means effective.
- 20 6. In a door lock, in combination, inner and outer knobs, a spring-pressed bolt having projections thereon, a sleeve extending between said knobs, a rod arranged in said sleeve slidably and nonrotatively thereto, a 25 disk carried by said rod to engage with said projections to prevent withdrawal of the bolt, and means in the inner knob operable at will to move the rod to bring the disk into or out of engagement with said 30 projections.
7. In a door lock, in combination, a spring-pressed bolt, a sleeve passing through said bolt, a knob connected to said sleeve at one end thereof, a second knob 35 mounted loosely on the other end of said sleeve, means adapted to coact with said bolt to withdraw the same connected to said second knob, means including a rod extending between the knobs and arranged in said 40 sleeve to mechanically interlock said knobs at will, and means on the rod to engage the bolt to deadlock the bolt.
8. In a door lock, in combination, a spring-pressed bolt, a sleeve passing through said bolt, a knob connected to said sleeve at one end thereof, a second knob provided with a rack therein and mounted loosely at the other end of said sleeve, means adapted to coact with said bolt to withdraw the same connected to said second knob, a rod in said 45 sleeve, a dog carried by said rod, means in the first knob controlled by a key to move said rod to have the dog engage with said rack, and setting mechanism in the second knob to move said dog into or 50 out of engagement with said rack at will.
9. In a door lock, in combination, a spring-pressed bolt provided with projections thereon, a sleeve passing through said bolt, a knob connected to said sleeve at one 55 end thereof, a second knob provided with a rack therein and mounted loosely at the other end of said sleeve, means adapted to coact with said bolt to withdraw the same connected to said second knob, a rod in said 60 sleeve, a spring-pressed dog on said rod to engage with said rack, means on said rod to engage the projections on said bolt, means in the first knob controlled by a key to move said rod longitudinally in said sleeve, and 65 setting mechanism in the second knob controllable at will to move said rod longitudinally in said sleeve, substantially as described and for the purposes set forth.

In testimony whereof, we have signed our 75 names to this specification in the presence of two subscribing witnesses at Los Angeles, county of Los Angeles, State of California, this 11th day of October A. D. 1909.
